UNITED STATES PATENT OFFICE.

WILLIAM H. BLATCHLEY, OF PITTSBURGH, PENNSYLVANIA.

REFRACTORIES PROJECTOR.

Application filed March 24, 1921. Serial No. 455,047.

To all whom it may concern:

Be it known that I, WILLIAM H. BLATCHLEY, a citizen of the United States, and a resident of Pittsburgh, in the county of Allegheny and State of Pennsylvania, have invented a new and useful Improvement in Refractories Projectors, of which the following is a specification.

This invention relates to apparatus for projecting material into a furnace. More particularly the invention is concerned with means for throwing granular refractory material into the back of an open hearth furnace, for building up the bottom thereof, or patching a hole therein.

The objects of the invention are to provide apparatus which may be charged outside the furnace, and which may be used to project the granular refractory material to any desired part of the furnace bottom or wall in the form of a mass of fine material, which mass will be more or less coherent, somewhat like a shovelful of such material projected manually. Other objects of the invention comprise a receptacle of special form and mounting for holding the fine material that is to be discharged, means for cushioning the projecting stroke, and generally a construction rendering such apparatus efficient and practical.

Referring to the drawings Fig. 1 is a plan view of my apparatus, with all superfluous parts removed; Fig. 2 is a side elevation thereof; and Fig. 3 is a partial vertical section on the line 3—3 of Fig. 2.

In building up open hearth furnaces, material of a highly refractory nature, such as magnesite or dolomite, is used. This is ordinarily prepared by a burning operation in a rotary kiln, then granulated, and shipped to the steel works. In making open hearth furnace bottoms it is customary to form a base of refractory bricks, and then to apply successive layers of granular refractory material. The heat of the furnace is continuously applied, each layer is exposed to this heat for some time, the material fuses or bonds together, and the successive layers so applied form a composite mass or wall, similar to concrete. This wall after setting under heat is strong enough to support the molten steel that is refined in such furnaces.

Heretofore it has been customary to charge granular refractory material into the furnace for building the bottoms thereof, by shoveling by hand, or by blowing it in with

an air blast. The latter method is objectionable because the air blast stirred up a great deal of dust, which settles in and clogs up the checker work of the furnace recuperator. The first method is likewise objectionable, as it exposes the workmen to intense heat, and the material is not properly placed. Furthermore, it is difficult to accurately measure the material with either of the two means above referred to.

My invention provides means to project measured charges of the granular material into the furnace properly directed so that they will be applied to the furnace bottom at the desired points, substantially in the form of loose masses. A minimum of dust is stirred up, and it is not necessary to water-cool the mechanism used for such projection.

Referring to the drawings, which illustrate an apparatus suitable for carrying out my invention, a base member comprising a plate 1, side frames 2, and mounted upon wheels 3 is adapted to move along the line of furnaces upon tracks 4. An upright member 5 is positioned at the middle point of the table, and pivotally mounted thereon and free to turn with respect to the table or plate 1, is a supporting member 6, which carries a lateral extension 7, to which is attached a small gear 8, meshing with a circular rack 9, fixed on top of the table 1; means not shown are provided to drive the gear 8.

The member 6 carries at its top bearings for trunnions 11 fixed on the outer sides of two rigidly connected frame members 20. These frame members are in the form of channel irons as illustrated in Fig. 3.

Mounted upon cross members 21, which are bolted between the two frame members 20 are two aligned cylinders 25 and 26. The cylinder 25 has inlet and exhaust valves at each end, the inlet valves being connected to the pipes 30 and 31, and the valves being controlled by the members 32 and 33 as in standard steam engine practice. The cylinder 26 has slots 35 cut out of its intermediate portions, but has no other inlet or exhaust valves. Consequently the cylinder 26 forms an air dash pot at each end for a piston 36, fastened on the end of shaft 37, which extends through a stuffing-box in the cylinder head 38. The shaft 37 extends on through the cylinder 25, and carries inside that cylinder a piston 40 which is adapted

to be driven in each direction by fluid pressure controlled by the valve mechanism above referred to. Beyond the cylinder 40 the shaft 37 is connected to a container of 5 special form, adapted to receive granular refractory material which is to be charged into the furnace. This container comprises a back wall 50, side walls 51, and bottom 52, but it has no top and no wall at the forward 10 end. The bottom inclines slightly toward the open end of the shovel. Through the back wall 50 a series of perforations 54 is provided. A guard member 55 extending across the back wall 50 and riveted thereto 15 above the perforations 54, screens the perforations from any solid material that may be poured into the charging receptacle.

This receptacle is supported by rollers 60, which ride in a guide 61 mounted in the 20 frame members 20, as illustrated at the left of Figs. 1 and 2.

The frame members 20 are pivotally mounted on the trunnions 11 and supporting member 6. A pair of supporting bars 25 70 are attached to a rod 71, extending beneath the frame members 20. At their upper ends these bars carry a cross-bar 73, to which are attached a pair of swiveling head members 74, which carry gears 75, threaded upon screws 76, which extend down to and are pivotally connected to an extension 7 from the supporting member 6. Worms 78 on the shaft of the gear wheel 79 drive the wheels 75, and consequently 30 cause the screws 76 to move into or out of the members 74. A motor is provided for driving the wheel 79, and by this means the frame 20 may be raised or lowered out of its horizontal direction, as much as desired. The pinion 8 may be rotated to drive 35 the rack 9 through any desired angle. Therefore by these two means of adjustment the track formed by the frame members 20 may be given any desired angle of inclination and turned through any angle with 40 reference to the pin 5 as a center. Consequently the projecting mechanism may be directed at any desired point in a furnace.

Situated above the receptacle is a hopper 50 85, adapted to receive the granular refractory material from any suitable source, and to store it. This hopper is of course carried upon suitable extensions from the supporting member 6, and travels with the machine. A suitable mechanism is housed in the box 86 for delivering uniform charges from the hopper to the receptacle as desired.

The operation of this device is as follows: The machine is moved along the track 4 60 to proper position before an open hearth furnace, the bottom of which is to be built up. By driving the pinion 8 the frame is directed at the door of the furnace, and the desired inclination of the track is procured 65 by means of a screw member 76 as previ-

ously described. Then a charge of granular refractory material is dropped from the hopper 85 through the measuring mechanism held in box 86, into the receptacle 50. The fluid pressure, such as compressed air or steam is admitted to the cylinder 25, the piston being in the position as shown in Fig. 2. The latter is driven quickly forward the length of the cylinder, but is stopped at the forward end of the 75 stroke by reason of the dash pot formed at the left end of cylinder 26, when the piston 36 has passed beyond the ends of the slots 35. The result is to project the charge of refractory material in a loose mass into 80 the furnace and to the desired spot therein. The stroke may be made as rapidly as desired, by controlling the fluid pressure admitted to the cylinder 25, and by making that cylinder of suitable length. Immediately thereafter pressure is admitted to the other end of cylinder 25, withdrawing the receptacle for another charge. The operation is then repeated. As will be obvious, the stroke of the piston is cushioned at each end by means of the air dash pots at the ends of cylinder 26.

It is desirable that the charge of loose granular material be carried in as compact a form as possible, and in order that this 90 may be done the back wall of the receptacle is made either perpendicular, or inclined forwardly. This is to prevent the fine material from sliding back over the rear wall, which would be the case if that wall sloped 100 backward, as in the ordinary shovel form. In order that the mass of loose material may be permitted to leave the receptacle in a more or less coherent form, that is to say 105 not scattered or broken into anything like a stream of material, perforations 54 are provided on the back of the shovel. The screen 55 prevents any of the fine granulated material from getting into these holes to clog them up or to leak out. At the same 110 time when the charge suddenly leaves the receptacle, air is drawn in through the perforations 54 behind the screen 55, thus permitting the breaking of what would be 115 a partial vacuum behind the charge, and so permitting the charge to go forward as a mass. The inclined bottom of the receptacle and the air release behind permit the charge to leave the receptacle en masse and without appreciable resistance or friction, 120 and without being broken up or scattered.

I claim:

1. In an apparatus of the class described, a scoop for receiving granular refractory material and discharging it into a furnace, 125 said scoop comprising a vertical rear wall, perforations near the bottom of said wall, and a screen for said perforations.
2. In an apparatus for discharging refractory material into a furnace, a scoop for re- 130

- ceiving the refractory material, said scoop having a rear wall and an open front, a track for guiding the scoop, means to drive the scoop forward on the track at a high rate 5 of speed, and cushioning means to stop the scoop at the forward end of the travel.
3. In an apparatus for projecting granular refractory material into a furnace, a receptacle for receiving the granular material, a track for said receptacle, means to drive the receptacle forward at a high rate of speed, and a dash pot adapted to limit and cushion the forward movement of the receptacle.
- 10 4. An apparatus for projecting granular refractory material into a furnace, comprising a receptacle for holding the granular material, and means to project the receptacle forward to the mouth of the furnace and there to suddenly stop it, the receptacle comprising side walls, a rear wall, and an open front, and perforations in the rear wall near the bottom thereof whereby to admit air behind the charge of loose material as it leaves 20 the receptacle.
- 25 5. In a machine for projecting granular refractory material into a furnace, the combination of a receptacle adapted to receive, transport and discharge through its front end the granular material, a track to sup-
- port and guide said receptacle, fluid operated means to drive the said receptacle along the said track, cushioning means adapted to arrest the movement of the receptacle at each end of its travel, and means 35 to adjust the position of said track.
6. In a machine for projecting granular refractory material into a furnace, a receptacle open at its forward end adapted to receive, transport and discharge granular 40 material by forward stroke of the receptacle, a track adapted to support and guide the receptacle, means to drive the receptacle on the track, and means to cushion the movement of the said receptacle at each end of 45 its stroke, such cushioning means comprising a piston surrounded by a cylinder substantially open throughout its intermediate portion and closed at each end, said piston being coextensive with the length of the 50 stroke of the receptacle, whereby to form an air cushion to limit the forward and backward movement of the receptacle without interfering with its intermediate movement.
- 55 In testimony whereof, I have hereunto set my hand.

WILLIAM H. BLATCHLEY.
